UNITED STATES PATENT OFFICE.

ARTHUR G. BOOZER, OF TUCAPAU, SOUTH CAROLINA.

SHELL-ROLLS FOR SPINNING-MACHINES.

SPECIFICATION forming part of Letters Patent No. 709,298, dated September 16, 1902.

Application filed March 20, 1902. Serial No. 99,186. (No model.)

To all whom it may concern:

Be it known that I, ARTHUR G. BOOZER, a citizen of the United States, residing at Tucapau, in the county of Spartanburg and State 5 of South Carolina, have invented new and useful Improvements in Shell-Rolls for Spinning-Machines, of which the following is a specification.

This invention relates to certain new and 10 useful improvements in shell-rolls for spinning-machines, the object being to improve the construction thereof, provide antifriction-bearing devices, means whereby the shell-rolls will be self-adjusting to and from 15 the lower rolls, and means for lubricating the bearings; and with the above ends in view the invention consists in the construction and combination of the parts, as will be herein-after set forth.

20 In the accompanying drawings, which illustrate one practical embodiment of my invention, Figure 1 is an end view showing a saddle upon the top rolls and a stirrup which engages the saddle, the saddles and stirrup being shown in dotted lines. Fig. 2 is a front elevation of a shell-roll, showing one roll out of a horizontal line with its spindle. Fig. 3 is a sectional view, the section being taken through different parts. Fig. 4 is a part plan 25 and part section, the shells and outer sleeves being removed. Fig. 5 is a section on the dotted line 3 3, and Fig. 6 is a sectional view of a modification in which balls are used instead of rollers.

30 Referring to the drawings, 1 indicates the main arbor or bearing, upon which the saddles shown in dotted lines bear, the requisite degree of pressure being applied to the rolls by a weight connected to the stirrup. The 35 arbor or main bearing 1 has end flanges, and from its central portion to project laterally are hollow spindles 2 2, the ends thereof being closed by plugs 3 3. The openings through the spindles connect with an opening through 40 the arbor, which is internally threaded to receive one end of a tube 4. The tubes 4, carried by the arbors, pass into or through openings in the saddles to hold the rolls in place and at the same time provide oil-passages for 45 conveying lubricant to the bearings of the rolls. Upon the spindles are secured sleeves

5 5, the ends nearest the arbor 2 having flanges 6, and the internal diameter of these sleeves is much greater than the external diameter of the spindles. The sleeves and 55 spindles are movably connected by hollow trunnions 7 7, disposed at substantially right angles with the tubes 4, the sleeve being susceptible of a rocking movement on the spindle, so that the roll may adapt itself to inequalities either as to the size of the top roll, 60 the bottom one, or variations in the size of the yarn. By providing hollow trunnions, the openings being in line with each other to provide oil-passages, the openings may be 65 readily cleared of obstructions. The trunnions connect the sleeves to the spindle so that such sleeves may have an oscillatory movement, the fulcrums being at the center of the spindles, and said sleeves provide race- 70 ways for rolls which are arranged in circular series, the flanges forming bearings for the inner ends thereof, the outer ends of the sleeves being threaded for the reception of nuts 8 8. The outer sleeve 9, which revolves 75 on the rollers 10, has an annular inwardly-extending flange against which the inner nut will abut, the outer nut serving to lock the inner one in place, and these nuts are of less diameter than the internal diameter of the 80 shells 11, which tightly embrace and turn with the outer sleeves 9. The shells are covered in the usual manner and are of sufficient length to extend over the nuts. To lubricate 85 the bearings of the rolls, oil is fed through the tubes 4, from thence flows into the hollow spindles, and passes as required through the hollow trunnions to the raceways of the rolls, and owing to the construction there is but little liability, if any, of the oil coming 90 in contact with the faces of the rolls or the yarn.

The construction shown by Fig. 6 admits of balls being used instead of rollers, and when such construction is desired the ends 95 of the outer sleeve are beveled and balls of the requisite size are used, such balls having their bearings against the end of the sleeve, they being retained at one end by the flange 6 and at the other end by the inner nut 8. The 100 lubricant passes to the raceways through the hollow trunnion 7. The nuts, which are cir-

cular, are provided with notches or recesses, so that they may be removed by a suitable wrench.

Having thus described my invention, what 5 I claim as new, and desire to secure by Letters Patent, is—

1. In shell-rolls for spinning-machines, the combination of a hollow arbor and spindles, an oil-duct through the arbor which commu-
10 nicates with the chamber within the spindles, sleeves of larger interior diameter than the exterior diameter of the spindles, hollow trun-
15 nions which connect the inner sleeves to the spindles and at the same time provide oil-
20 passages between the chamber in the spindles and the exterior of the inner sleeves, outer
25 sleeves rotatively mounted on the inner sleeves, and antifriction - rolls between the
30 shells, substantially as shown.
2. In top rolls for spinning-machines, the combination of non-rotative spindles, an inner shell pivoted thereto and capable of an oscillatory movement on the spindle, a nut carried by the outer end of the inner sleeve,
35 an outer sleeve rotatively mounted on the inner sleeve and held against longitudinal move-
40 ment in one direction by the nut, and anti-
friction-rolls between the shells, substantially as shown.
3. In shell-rolls for spinning-machines, the combination of a hollow arbor and spindles

constructed to provide an oil-duct between the arbor and the spindles, an inner shell with flanges adjacent to the arbor and screw-threads near their outer ends, hollow trun-
35 nions pivotally connecting the inner shells to the spindles and providing oil-passages from the hollow spindles to the outer faces of the inner shells, nuts on the screw-threaded ends of the inner shells, antifriction-rolls between the shells and also between the flanges and nuts on the inner shells, and a shell-roll of sufficient length to cover the outer shell and the nuts, substantially as shown.

4. The combination with a non - rotative 45 spindle, an inner shell of greater internal diameter than the external diameter of the spindle, hollow trunnions between the spindle and inner shell, an outer shell rotatively mounted on the inner oscillatory shell, a shell-roll car-
50 ried by the outer rotary shell, and means re-
movably connected to the non-rotative shell to hold the outer shell against longitudinal movement thereon, substantially as shown.

In testimony whereof I have hereunto set 55 my hand in presence of two subscribing wit-
nesses.

ARTHUR G. BOOZER.
